J. H. STONE.
SHEET METAL CAN.

No. 82,766.

Patented Oct. 6, 1868.

United States Patent Office.

JOHN H. STONE, OF PHILADELPHIA, PENNSYLVANIA.

Letters Patent No. 82,766, dated October 6, 1868; antedated September 26, 1868.

IMPROVEMENT IN SHEET-METAL CANS.

The Schedule referred to in these Letters Patent and making part of the same.

TO ALL WHOM IT MAY CONCERN:

Be it known that I, JOHN H. STONE, of the city of Philadelphia, in the State of Pennsylvania, have invented a new and useful Improvement in Sheet-Metal Vessels; and I do hereby declare that the following is a full, clear, and exact description of the construction and operation of the same, reference being had to the accompanying drawings, making a part of this specification, in which—

Figure 1 is a longitudinal central section of a powder-can having my said improvement applied thereto.

Figure 2 is a sectional portion of fig. 1 enlarged, and

Figure 3 a plane view of the mouth-closing slide.

Like letters of reference indicate the same parts when in the different figures.

The object of my improvement is to give additional strength and protection to the lap-joint, which is usually formed between the end and side plates of sheet-metal cans and other vessels, and to the chime or rim which is formed by the said joint, and projects around and beyond the flat end plates of such vessels, and also to afford a more simple and secure device for closing the mouths of such sheet-metal vessels as require small mouths.

My invention consists in applying and securing the end plates to the side plates of sheet-metal vessels, by means of an inside bead in combination with a broad lap-joint, consisting of three thicknesses of the sheet metal compressed together, and then bent so as to produce a strong, close joint, having a flange projecting at about a right angle therefrom, around on the inner side of the same, substantially as hereinafter described and shown.

And my invention also consists in the construction and application, substantially as hereinafter described and shown, of a sliding cover for the mouths of such sheet-metal vessels as require small mouths, as powder-cans, &c.

In the drawings, A A represent the opposite sides of a powder-can; B B, the opposite ends of the same, a' being the bead, and c d the lap-joint and flange; and E F the sliding stopper for the mouth of the vessel.

The beads a' a' are produced around on the inner side of A, by an annular groove or indentation made in the outer side, at a suitable distance from each of its ends, so as to form a shoulder, a', for supporting the respective end plates B. Each of the said end plates B has its edge c first turned at a right angle, and then inserted within the end of the body of the intended vessel, so as to fit the same, and rest upon the bead a' with its turned edge outward, the width of said turned edge c of the said end plate, being about half the width of that part of the side plate A which projects outward from the bead a'. This latter part of A is now bent inward and downward over the projecting edge c of B, and the three parts then pressed closely together, thus forming a broad, close joint c d, consisting of three thicknesses of the metal. The upper half of this lap-joint is now turned inward, until brought parallel to the surface of the end plate B, or so as to produce the inside annular flange d, substantially as represented in figs. 1 and 2.

The sliding stopper or cover E F for the mouth of the can, consists of a small, square plate, F, of the sheet metal, having a hole punched through its middle, about a quarter of an inch less in its diameter than the diameter of the mouth-hole in the can, over which latter the said plate F is applied, and secured by turning the projecting edge of its hole down under the edge of the hole in the plate B, and then swaging it close under the edge of the plate around the hole in the said plate B, the two side edges f' f' of the plate F, being previously turned over inward, so as to form lips for receiving, guiding, and holding the slide E, as shown in figs. 1 and 3. The slide E is a flat piece of sheet metal, cut of proper width to slide within the two laps f' f', its outer end e' being bent over upon it, so that the slide E will thereby catch over the entering ends of f' f', when it is pushed inward, so as to cover the mouth of the can, and its inner end notched out so as to leave two projections, e'' e'', which can be turned up and over upon the corresponding ends of f' f', as indicated by the dotted line in fig. 1, and thus fasten the slide securely in place when closed, and at the same time admit of its being easily released by turning the projections e'' e'' back again when it is desired to open the can.

This improvement in sheet-metal vessels is of great importance to manufacturers of gunpowder, white-

lead, and others who require very strong and tight-jointed cans, because such vessels are liable to frequent exposure to the weather, and to rough handling in transportation; and it will be seen that the parts most liable to damage, *i. e.*, the projecting rims, are by this construction strongly supported by the internal flange *d*, and that, at the same time, the greater extension or breadth of the joint produced, increases its tightness and durability as such.

The sliding stopper *E F* affords a perfectly secure and easily constructed and applied cover for the mouth of the vessel, and one that is not liable to be easily knocked off or broken open in handling the vessel roughly.

Having thus fully described my improvement in sheet-metal vessels, what I claim as new therein of my invention, and desire to secure by Letters Patent, is confined to the following, *viz*:

1. I claim, in combination with the internal bead *a'*, a lap-joint consisting of three thicknesses of the sheet metal pressed closely together, and the upper half of the same then bent inward to a right angle, so as to produce the annular flange *d* around on the inner side of the chime of the vessel, and parallel with the end plate of the same, substantially as set forth and described, for the purposes specified.

2. I also claim the sliding stopper or cover *E F*, constructed and operated as set forth, for the purpose of closing the mouths of sheet-metal vessels, as described.

J. H. STONE.
